(57) CLAIM

The ornamental design for a tobacco pouch wallet, as shown and described.

DESCRIPTION

FIG. 1 is a front perspective view of a tobacco pouch wallet;
 FIG. 2 is a front elevation view thereof;
 FIG. 3 is a rear elevation view thereof;
 FIG. 4 is a right side elevation view thereof;
 FIG. 5 is left side elevation view thereof;
 FIG. 6 is a top plan view thereof;
 FIG. 7 is a bottom plan view thereof;
 FIG. 8 is a top perspective view thereof; and,
 FIG. 9 is a rear perspective view thereof.
 The broken lines in the drawings illustrate portions of the tobacco pouch wallet which form no part of the claimed design.
